UNITED STATES PATENT OFFICE

HENRY L. RADWAY, OF CLEVELAND, OHIO

PROCESS OF AND APPARATUS FOR APPLYING STENCIL DESIGNS

Application filed September 13, 1929. Serial No. 392,342.

This invention relates to a process of and the apparatus for applying stencil designs, particularly to such process and apparatus for applying stencil designs to painted or enameled metal ware.

One of the objects of this invention is to provide automatic means for holding a stencil on metal ware while a design is being applied thereto through the stencil.

Another object is to provide magnetic means for holding a stencil against a metallic surface on which an enameled or painted design is to be applied through the stencil, the magnetic means being particularly adapted to firmly hold the edges of the stencil against the surface to prevent the paint or enameling fluid from creeping under the edges of the stencil.

Another object is to provide such a device which, in addition to holding the stencil in place while the design is being applied, is adapted to heat the surface in order to quickly dry the stenciled design.

A further object is to provide a novel process of applying stencil designs and the like to enameled metal ware. With the above and other objects in view, the present invention may be said to comprise the apparatus, as illustrated in the accompanying drawings and the procedure of carrying out the invention, hereinafter described and particularly set forth in the appended claims, together with such variations and modifications thereof as will be apparent to one skilled in the art to which the invention appertains.

In the drawings, which illustrate a suitable embodiment of the present invention,

Figure 1 is a plan view of the magnetic stencil holding device, showing the general arrangement of the magnet poles and showing fragmentary portions of a metal member and a stencil disposed thereover.

Fig. 2 is a longitudinal section taken substantially on the line 2-2 of Fig. 1.

The present invention is particularly adapted for use with vitreous enameled metal articles on which it is desired to apply a figure or design through a stencil. The design is usually of a different color than the enamel coating and is applied before the coat-

ing is fused or vitrified, so that the coating and the design can be fused in a single operation. The vitreous enamel for the design usually comprises a water suspension of finely divided oxides and is sprayed on the enamel 53 coating through a stencil.

Heretofore considerable difficulty has been experienced in holding the stencil in such close contact with the article that the enamel suspension would not creep underneath the edges of the stencil. It is obvious that if the enamel did creep underneath the edges of the stencil the design would have ragged, uneven edges. This is especially true of the unfused enamel base coat, which has a tendency 60 to absorb the design enamel being applied. Furthermore, when the base coat and enamel are vitrified the enamel which has run underneath the edges of the stencil will have a tendency to blend in with the base coat and produce a gradual fading out of color of the 65 design and prevent a distinct line of demarcation between the base coat and the design.

The present invention proposes a magnetic arrangement, which is adapted to be positioned inside the metal article to be provided with an enameled design, which will firmly hold all the edges of a metallic stencil in close contact with the outer surface of the article.

Vitreous enamel, as previously mentioned and as used for sheet metal, usually comprises a water suspension of finely divided oxides and before the enamel can be fused or vitrified the water must be evaporated. The present invention comprises means for greatly accelerating the evaporation of the volatile ingredients of the enamel, so that considerable time can be saved between the enameling and vitrifying operations. Another important advantage in applying the design to an unburned coat of enamel is that blistering of the design enamel and the making of water lines is substantially eliminated.

Referring to the accompanying drawing, in which like numerals refer to like parts throughout the several views, the magnet arrangement comprises a suitable base 10 having a plurality of pole pieces 11 secured thereto in closely spaced relationship by screws 12, or any other suitable means. These pole

pieces 11 are preferably of thin rectangular shape, preferably of about $\frac{1}{16}$ inch thickness, and are positioned on the base 10 in vertical parallel relationship. In order to obtain the greatest efficiency from the device the poles 11 are preferably spaced at about one inch intervals. They may, however, be spaced as far apart as two inches or as close as half an inch. This is, of course, dependent somewhat on the size of the device and the size of the stencil to be held. The windings 13 are so arranged that adjacent poles will be of opposite polarity, that is, one pole will be of negative polarity and the two adjacent poles 15 will be of positive polarity.

The upper end faces of the pole pieces 11 are substantially flat and lie in the same horizontal plane if the device is to be used with an article having a flat surface. However, if 20 the article to be enameled has a curved surface the end faces of the pole pieces 11 are preferably arranged to lie in a curved plane, having the same general curvature as the article. Side and end pieces 14 are preferably secured to the base 10 by screws 15 to completely enclose the magnet device with the exception of the ends of the pole pieces 11 which are left exposed.

The magnet is placed inside the article 16 30 to be enameled or against the side opposite the side to be enameled and the stencil 17 is positioned against the side to be enameled in the vicinity of the magnet. The end faces of the pole pieces 11 all lie in the same plane, 35 providing a suitable supporting surface for the article 16 upon which the stencil 17 of magnetic material is positioned.

It is obvious that the stencil completes the magnetic circuit and provides a path for the 40 lines of magnetic polarization 19, as shown in Fig. 2, between opposite poles of the magnet device. It will be observed that the pole pieces 11, being in rather closely spaced relationship, greatly increase the magnetic effect 45 which causes all the edges of the stencil defining the design 18 to be very firmly held against the surface of the article 16.

The enamel suspension for the design is sprayed through the stencil 17 and it is 50 readily apparent that the edges defining the design 18, being in firm contact with the article 16, will prevent the suspension from seeping, or otherwise working underneath the stencil. It is apparent that by holding 55 the stencil in this way a design having a distinct line of demarcation with respect to the base coating of the article can be produced.

In cases where the enamel design is applied to a metallic article having an unfused base 60 coating, the magnet windings 13 are preferably of such size, or rather such diameter of wire, that in addition to holding the stencil against the article being enameled, they form resistor units that develop considerable heat. 65 It is readily apparent that the heat thrown

off from the windings 13 will, in this case, quickly heat the article 16 so that the volatile ingredients of the enamel suspension used in applying the design will be rapidly evaporated.

It is obvious that the magnet serves a dual purpose, that of holding the stencil in position while the design is applied and of substantially simultaneously evaporating the volatile ingredients of the suspension and 75 consequently drying the design which has been applied. In this way considerable time is saved between the stenciling and fusing operations and also storage space is dispensed with because it is unnecessary to lay the 80 articles out so that the articles can be dried previous to the fusing operation.

The device described and shown in the drawing has been found in practice to successfully hold the edges of the stencil in close 85 contact with the article being decorated to prevent seeping of the enameling suspension, and to quickly dry the enamel design which has been applied.

Furthermore, it is to be understood that the particular forms of apparatus shown and described, and the particular procedure set forth, are presented for purposes of explanation and illustration and that various modifications of said apparatus and procedure can 90 be made without departing from my invention as defined in the appended claims.

What I claim is:

1. In a device of the class described, a magnet device for holding a magnetic stencil in close relationship with the article being stenciled, comprising a base, a plurality of relatively thin rectangular pole pieces secured to said base in closely spaced parallel relationship and having their ends substantially in the same plane to support the article, and windings for said pole pieces so arranged as to provide each pole with opposite polarity with respect to the adjacent pole pieces, whereby the edges of the stencil will be firmly held against the article being stenciled, said windings being of sufficient resistance to rapidly heat said article and quickly vaporize the volatile ingredients of the stenciling fluid applied through said stencil.

2. The method of forming stenciled designs on metallic articles having unfused vitreous enamel coatings, which consists in magnetically holding the edges of the stencil defining the design to be applied firmly in close contact with the enameled surface, applying the stenciling medium through said stencil onto said enameled surface, and simultaneously heating said surface to substantially drive off the volatile ingredients of the stenciling medium upon the application of said medium to said surface.

3. In a device of the class described, a magnet device for holding a magnetic stencil in close relationship with the article being

stenciled, comprising a plurality of transversely disposed pole pieces in closely spaced relationship, having their end surfaces in substantially the same plane to support the article upon the pole pieces, adjacent pole pieces being of opposite polarity and the windings of said pole pieces being of sufficient resistance to heat the article being stenciled and quickly dry the surface being 10 stenciled.

In testimony whereof I affix my signature.
HENRY L. RADWAY.
